WELL DRILLING EQUIPMENT

John H. Schreiber, St. Louis, Mo.

Application July 2, 1945, Serial No. 602,787

20 Claims. (Cl. 254—173)

1

This invention relates to well drilling equipment; and it has special reference to a cathead and joint breaker device of the type used in the well drilling industry.

The cathead proper comprises a spool removably attached to one end of the rotary draw-works shaft of a drilling rig for constant rotation thereby when said shaft is rotating. Said draw-works shaft is rotated in one direction in joint-breaking operations, but is sometimes rotated in the opposite direction in other operations. The joint breaker comprises a drum that is cooperatively associated and combined with said cathead. The present invention is an improved modification of the invention disclosed in my prior application Serial No. 569,702, filed December 26, 1944, for patent for Well drilling equipment, and has the spool and the drum detachable from each other. As in said prior application, the joint breaker of the present invention comprises a shoe rigidly attached to one end of a longitudinally movable and flexible jerk line, and one or more pin elements carried by the rotating drum of the joint breaker for engaging said shoe to move said jerk line longitudinally in one direction to a greater extent than has heretofore been possible in joint breakers of the type in which the present invention is contained. In attaining these beneficial results, I provide a device having a relatively small drum capable of effecting a relatively longer movement of the flexible jerk line than has heretofore been possible when said jerk line is under tension.

One object of the invention is to provide an improved cathead and joint breaker having a rotary drum for intermittently and optionally moving a flexible jerk line longitudinally, comprising a pair of axially aligned removable pins on said drum for engaging a shoe attached to said jerk line, formations on said drum functioning to support and prevent deformation of said pins, and releasable elements for holding said pins in cooperative relationship and for preventing displacement thereof.

Other objects of the present invention are to provide an improved cathead and joint breaker having a removable pin, or a pair of longitudinally aligned removable pins, for positively and pivotally engaging the jerk line shoe to move said jerk line longitudinally in one direction, and novel means removably holding said pin or pins in effective position on the rotary drum so that, at the time desired, said pin or pins will be engaged by the jerk line shoe and will move said shoe in a planetary path about the axes of the

2

drum in order to move said jerk line longitudinally in one direction; to provide devices for holding and preventing displacement of said respective removable pins while holding said pins separately removable from the drum; to provide a pair of axially aligned shoe engaging removable pins mounted on the drum and separated by an intervening space for receiving the body portion of the shoe having laterally extended hook-shaped flanges for positively and pivotally engaging said pins; and to provide a stationary cam enclosed within said drum for disengaging said shoe from said pins and thereby leaving the jerk line and the shoe free to move and return to their initial starting positions while the drum continues to rotate.

Other objects and advantages will appear from the following description, reference being made to the annexed drawing, in which—

20 Fig. 1 is a longitudinal sectional view of my improved cathead and joint breaker showing the jerk line shoe in position to be engaged by two axially aligned pins on the rotary drum of the joint breaker device.

25 Fig. 2 is a vertical cross-sectional view taken approximately on the line 2—2 of Fig. 1, and showing the jerk line shoe in the position to which it is moved by the controlling socket for engagement by the pins on the rotating drum as in Fig. 1.

30 Fig. 3 is an enlarged sectional view showing the inner end of one of the removable pins on the rotating drum for engaging and operating the jerk line shoe to move the jerk line longitudinally, and also showing a formation on said drum functioning to support and prevent deformation of said pin.

35 Fig. 4 is a sectional view on the line 4—4 of Fig. 3, showing one form of a device for holding one of the removable pins from displacement, and also showing said formation for supporting and preventing deformation of said pin.

40 Fig. 5 is a view showing a modified form of device for holding one of the removable pins from displacement, and also showing in dotted lines said formation for supporting and preventing deformation of said pin.

45 Fig. 6 is a sectional view on the line 6—6 of Fig. 5, showing additional features of said modified form of holding device for the removable pin.

50 Fig. 7 is a greatly enlarged view showing a portion of the periphery of the rotary drum, and also showing another form of device for holding the respective removable pins from displacement.

Fig. 8 is a similarly enlarged sectional view on the line 8—8 of Fig. 7.

The hollow cylindrical element 1 is designed and intended to be mounted on and attached to the usual rotary drawworks shaft for rotation thereby. Said element 1 is rotated in one direction by said shaft in joint-breaking operations, and in other operations is sometimes rotated in the opposite direction by rotation of said shaft in said opposite direction. Said element 1 constitutes a sleeve for receiving the end portion of the rotary drawworks shaft to which it is to be detachably secured. Said sleeve 1 has a radial flange 2 integral with its inner end functioning as an abutment for one end member 3 of a bushing on which the hub 4 of the stationary housing 5 is supported, and also preventing longitudinal displacement of said housing. The other and complementary bushing member 6 is mounted on the outer end portion of said sleeve 1 and may be held from longitudinal displacement toward the bushing member 3 by the hub 4. The sleeve 1 has in its outer end a series of screwthreaded holes in which the studs 7 are secured. The hollow cylindrical cathead spool 8 has an inwardly extended flange 9 provided with unscrewthreaded holes through which said studs 7 project. Nuts 10 are screwed on the outer ends of the studs 7 and hold the spool 8 attached to the sleeve 1 for rotation thereby.

In the present construction, the rotary drum 11 is separate from the cathead spool 8 and is relatively mounted within the stationary housing 5, although said drum and spool may be integrally formed as disclosed in said prior application without departure from the principle of this invention. As shown, said drum 11 has a flange 12 extending inwardly against the outer end of the sleeve element 1 and provided with unscrewthreaded holes through which the studs 7 project. After the nuts 10 are tightened, said flange 12 of the drum 11 is held clamped between the flange 9 of the cathead spool and the outer end of the sleeve element 1. Two axially aligned and longitudinally spaced pins 13, constituting removable and replaceable elements for engaging the jerk line shoe, are secured on the drum 11 and are carried in a planetary orbit about the axis of the sleeve 1 and of the rotary drawworks shaft to which said sleeve is attached during rotation of said sleeve by said shaft.

Repeated and intermittent contact and engagement of said pins 13 with the jerk line shoe (hereinafter described), and sliding disengagement of said shoe from said pins 13, has a tendency to wear and to deform said pins 13. My present invention comprises elements attached to said drum engaging and holding the pins 13 in proper positions, and preventing longitudinal displacement thereof, and also facilitating removal and replacement of any worn or deformed pins 13 and replacement of unworn and undeformed pins in substitution for those that had become worn and deformed, and removed. My invention also comprises formations on the drum constituting mountings for said pins 13, and cooperating directly therewith, to prevent other deformation of said pins by said repeated contact and engagement of said pins with said brake shoe.

The two pins 13 are axially aligned, are mounted in the respective side flanges 14 of the rotary drum 11, and are separated by an intervening space 15. Said pins may be held from longitudinal displacement by releasable holders of different forms. As shown in Figs. 3 and 4, each pin 13 is formed

with a circumferential groove 16 receiving the two arms 17 of a device in the form of a forked plate 18. The plates 18 are attached to the outer sides of the respective flanges 14 by removable screws 19 holding said devices 17—18 attached to the outer sides of said flanges 14 of the drum 11 to prevent longitudinal displacement of the pins 13, making it possible to mount said pins in any angular positions about their respective axes. 5 The aforesaid formations on the drum which constitute mountings for said pins 13 and which prevent bending deformation of said pins by said repeated contact and engagement of said pins with said brake shoe, and the strains and stresses 10 imparted by the jerk line, comprise arcuate shoulders 14a integral with the drum 11 and the two flanges 14 along the two adjacent corners formed by said drum and said flanges (Fig. 1). The said shoulders 14a are separated by a space having 15 approximately the same width as said space 15 between said pins 13, so that the adjacent surfaces of said shoulders 14a are approximately flush with the adjacent ends of said pins 13. The forward ends of said two flanges 14a have bearing contact with and against rear and inner peripheral portions of the surfaces of said two pins 13, thereby preventing bending, shearing and analogous deformations of said pins 13 by repeated 20 contact and engagement of said pins with the 25 brake shoe hereinafter described, and the strains and stresses imparted by the jerk line. These 30 are important features of the present invention. They very considerably prolong the durability or period of utility of the device, and they make 35 possible repair of the joint breaker on the ground and in the field by removal and replacement of said pins 13 without long delay, as would necessarily occur in the case of joint breakers in which welding or other analogous repairs are required. 40 These repairs which may be made without inconvenience and without long delay, and on the ground of operations, recondition the joint breaker as though the repaired damage had never 45 occurred. The screws 19 are preferably secured to the plates 18 in a manner to prevent said screws from loosening after they have been tightened. As shown, pieces of wire 19a pass through holes in the heads of the respective screws 19 and through complementary adjacent holes in the plates 18 and thereby interlock said screws and 50 said plates. This effectively prevents the screws 19, the plates 18 and the pins 13 from becoming displaced after they have once been properly assembled. 55 Pins 20 may be used in substitution for the pins 13. Each pin 20 is preferably of hollow cylindrical form and provided with an internal annular cam 21 engaged by a spring arm 22. The cams 21 are between and inwardly from the 60 ends of said pins, so that said pins may be reversed or initially mounted end for end without modifying their functions in any way. The spring arms 22 are formed integral with plates 23 attached to the outer sides of the respective side flanges 14 of the rotary drum 11 by detachable 65 screws 24 having holes through their heads for receiving locking devices 25 to prevent accidental turning or loosening of said screws after said screws have been tightened. The plates 23 of the 70 holders 22—23 engage against the outer ends of the respective pins 20 and positively prevent outward displacement of said pins, while the spring arms 22 engaging against the inner surfaces of the cams 21 prevent inward displacement of said 75 pins 20, making it possible to mount said pins in

any angular positions about their respective axes. Each pin 20 has a groove 20a, or other formation, intermediate of its ends for engagement by any suitable implement to move said pins longitudinally in inward directions for purposes of removal and replacement. The pins 20 are of the same length as the pins 13, and cooperate with the ends of the formations 14a in the same way as do the pins 13.

A jerk line 26 composed of wire rope or cable extends through a hole 27 in a shoe supporting and operating member 28. Said member 28 is mounted on a pivot 29 carried by the stationary housing 5. A spring 30 connecting an arm 31 extending from the member 28 with a rigid arm 32 projecting from the stationary housing 5, yieldingly holds said member 28 in its initial unoperated position in which an extension 33 on said member engages and overlaps a part 34 on the stationary housing 5 until said member 28 is operated by the arm 31. The jerk line shoe shown is of the form disclosed in my said application Serial No. 569,702, filed December 26, 1944, and is attached to the end of the jerk line 26 at the inner end of the member 28. The body 35 of said shoe is of less thickness than the width of the space 15 between the adjacent ends of the pins 13 and 20, which is substantially equal to the distance between the arcuate shoulders 14a, so that said shoe may be moved into said space 15 by the shoe engaging member 28 to position in which said pins will engage the two shoe hook flanges 36. The shoe body 35 cooperating with the arcuate shoulders 14a, and the hook flanges 36 cooperating with the drum flanges 14, positively prevent turning displacement of the shoe 35-36 at all times. Said shoe is thereby located and held at rest in proper adjustment for movement by the member 28 to a position in which the pins 13 or the pins 20 will engage the hooks 36 as described.

A stationary cam 37 formed integral or rigid with the hub 4 of the stationary housing 5 is engaged by the inner edge of the shoe body 35 at the proper time during movement of said shoe body by the pins 13 or 20. Said cam functions to move the shoe 35-36 outwardly far enough to permit said pins to disengage and pass beyond the ends of the hook flanges 36 and thereby cooperate with the inherent and natural tendency of the wire rope or wire cable jerk line 26 to straighten and thus effect final disengagement of said pins from said hook flanges, leaving the jerk line 26 free to return the shoe 35-36 to its initial or starting position in the operating member 28. In order that the shoe body 35 may move inwardly far enough to a position in which the pins 13 and 20 may engage the shoe hooks 36, and may then engage the stationary cam 37 to disengage said hook flanges 36 from the pins 13 and 20, an arcuate slot 38 is formed in the drum 11.

The said slot 38 extends entirely through the drum 11. The stationary cam 37 is shown as an eccentric formation on the stationary hub 4 and has its high point approximately in contact with or close to the inner periphery of the drum 11 and does not interfere with or restrict the free rotation of said drum about said stationary hub 4. The drum 14 with its integral arcuate shoulders 14a prevent movement of the shoe 35-36 by the member 28 far enough toward the axis of said drum to a position in which the pins 13 and 20 will engage the hooks 36 until the slot 38 is opposite and permits said movement of said shoe toward the axis of said drum. At the sides of

the slot 38, the arcuate shoulders 14a are of reduced radial thickness in order not to prevent inward movement of the shoe 35-36 by obstructing the said shoe hooks 36. When the shoe 35-36 is moved by the member 28 to position to be engaged by the pins 13 or 20, said shoe extends through the slot 38 close to the periphery of the housing hub 4. After and while the hook flanges 36 are engaged by said pins, the shoe 35-36 is moved in a planetary course about the axis of the drum 11 and, after a predetermined extent of travel, the shoe body 35 engages and operates against the cam 37 and is thereby moved outwardly and disengaged from the pins 13 and 20, as described. Said pins are mounted near the rear end of the slot 38 so that the jerk line 26 will be wound on and about the drum 11 during rotation of said drum. An inclined cam surface 39 is formed on the drum 11 at the opposite or rear end of the slot 38 in order to engage and slide over the shoe 35-36 and to prevent the drum from abutting against and damaging said shoe and other parts during reverse rotation of said drum, as before mentioned. The housing 4-5 is secured against rotation by attachment of an integral lug 40 as a stationary support, leaving the cat-head and joint breaker free for rotation by the sleeve element 1 and the shaft to which said element is attached. Said parts continue to rotate without operating the jerk line 26 until the engaging member 28 is moved in opposition to the tension of the spring 30 in order to move the shoe 35 into the slot 38 to a position for engagement of the pins 13 and 20 with the hook flanges 36 of said shoe. After the pins 13 and 20 have engaged the hook flanges 36, the shoe will be moved with the rotating drum 11, and the jerk line 26 will be wound on said drum until the hook flanges 36 are disengaged from the pins 13 and 20 by the cam 37, or otherwise.

Formation of the rotary drum 11, etc., construction of the pins 13 and 20, and the releasable elements for holding said pins in cooperative relationship with each other and for preventing disengagement thereof, may be varied in other equivalent particulars without departure from the principle of the invention. As shown enlarged in Figs. 7 and 8, the drum 11 may extend laterally beyond the outer sides of the two circumferential flanges 14 to provide edge margins 41. Bosses 42 are formed integral with the laterally extended margins 41 and with the outer sides of the flanges 14, instead of being formed integral with the outer sides of said flanges only, as in the construction already described. Two axially alined pins 43, in substitution for the two axially alined pins 13 and the two axially alined pins 20, are mounted in holes provided for said pins through said bosses 42 and through the flanges 14, the same as the pins 13 and 20. The two axially alined pins 43 are separated by an intervening space 45, as are the two pins 13 and the two pins 20. The pins 43 have their inner ends approximately flush with the adjacent surfaces of the forward ends of the formations on the shoulders 14a against which the rear and inner peripheral surfaces of said pins bear and abut, leaving the front and inner peripheral surfaces of said pins 43 exposed for engagement by the hook flanges 36. The outer ends of said pins 43 are approximately flush with the outer surfaces of the bosses 42, so that the length of each of said pins is approximately equal to the combined thickness of the boss 42, flange 14 and formation on the shoulder 14a in and against which said pins are

respectively secured for engagement by the hook flanges 36 of the shoe 35-36.

Annular slots 44 extend from the respective holes in which the pins 43 are mounted to the peripheral surfaces of the flanges 14 and bosses 42 providing tongue devices 45 attached to the drum 11 for engaging and holding the pins 43 from displacement in any direction. Screws 46 extend through holes in the devices 45 and have screwthreaded engagement in screwthreaded holes 47 inwardly beyond said devices 45 for securely bending and clamping said devices 45 on the pins 43 to hold said pins from displacement in any direction. The heads 48 of the screws 46 are received and contained in recesses 49 formed in the bosses 42 and flanges 14. After the respective screws 46 are tightened, and after the elements 45 are thereby bent in opposition to their inherent resiliency and engaged with and hold the pins 43 from displacement, the metal around the open ends of the holes 49 is peened or otherwise deformed to provide inturned formations 50 clampingly engaging the screwheads 48 and thereby holding the screws 46 from turning and loosening. The devices 45 are thus held in engagement with and prevent displacement of the pins 43. When it is desired to remove any pin 43 for replacement or other purposes, it is only necessary to remove the formation 50, manually loosen the screw 46, and permit the device 45 to spring outwardly, releasing and permitting removal and replacement of said pin 43. After any pin 43 has been removed, another similar pin may be substituted therefor, the screw 46 tightened to clamp the device 45 against the newly substituted pin 43, and another formation 50 peened to prevent the screw 46 from turning and loosening.

The operation of my improved joint breaker, or combined cathead and joint breaker, is evident to one skilled in the art to which it appertains from the foregoing description. My invention attains all of its objectives and purposes efficiently and economically and provides means whereby any worn or damaged pins 13 and 20 may be conveniently removed and replaced when needed to recondition the device for further use and operation. In this invention, as in the invention disclosed in my copending application Serial No. 569,702, I utilize a cathead having a relatively small drum 11 capable of effecting a longer stroke of the jerk line than has heretofore been possible by use of joint breakers of this type. It is apparent that other specific variations than those specifically disclosed may be made in the construction and arrangement of the parts as do not depart from the nature and principle of the invention as defined by the appended claims.

I claim:

1. In a joint breaker having a rotary drum, a longitudinally movable jerk line, and a shoe attached to said jerk line for operation by said drum to move said jerk line longitudinally in one direction; flanges integral with said drum forming a circumferential space around said drum for said shoe, a pair of axially aligned pins extending through said flanges into said space for engaging said shoe to move said jerk line longitudinally as aforesaid, and formations on said drum engaging the rear and inner peripheral surface portions of said pins.

2. In a joint breaker having a rotary drum, a longitudinally movable jerk line, and a shoe attached to said jerk line for operation by said drum to move said jerk line longitudinally in one direc-

tion; a pair of circumferential flanges integral with said drum and separated by an intervening space for containing said shoe, two axially aligned removable pins extending through said flanges and having their adjacent ends separated by an intervening space for receiving the body of said shoe, hooks integral with said shoe for engagement by said pins to move said shoe with said drum and thereby move said jerk line longitudinally as aforesaid, and shoulders integral with said drum and said flanges engaging the rear and inner circumferential portions of said pins and preventing deformation of said pins by said hooks.

3. In a joint breaker having a rotary drum, a longitudinally movable jerk line, and a shoe attached to said jerk line for operation by said drum to move said jerk line longitudinally in one direction; a pair of circumferential flanges integral with said drum and separated by an intervening space for containing said shoe, two axially aligned removable pins extending through said flanges and having their inner ends separated by an intervening space for receiving the body of said shoe, hooks integral with said shoe for engagement by said pins to move said shoe with said drum and thereby move said jerk line longitudinally as aforesaid, shoulders integral with said drum and said flanges engaging the rear and inner circumferential portions of said pins and preventing deformation of said pins by said hooks, and releasable elements attached to said drum engaging and holding said pins from displacement.

4. In a joint breaker having a rotary drum, a longitudinally movable jerk line, and a shoe attached to said jerk line for operation by said drum to move said jerk line longitudinally in one direction; a pair of circumferential flanges integral with said drum and separated by an intervening space for containing said shoe, two axially aligned removable pins extending through said flanges and having their axes parallel with the axis of said drum and also having their inner ends separated by an intervening space for receiving the body of said shoe, hooks integral with said shoe for engagement by the forward and outer peripheral portions of said pins to move said shoe with said drum and thereby move said jerk line longitudinally as aforesaid, arcuate shoulders integral with said drum and said flanges engaging the rear and inner circumferential portions of said pins and preventing deformation of said pins by said flanges, elements engaging and holding said pins from longitudinal displacement, and screws attaching said elements to said drum.

5. In a joint breaker having a rotary drum provided with an elongated slot extending circumferentially, a stationary support on which said drum is mounted for rotation, a stationary cam rigid with said support within said drum, a longitudinally movable jerk line, and a shoe attached to said jerk line for operation by said drum to move said jerk line longitudinally in one direction; flanges integral with said drum forming a circumferential space around said drum for containing said shoe, a pair of axially aligned pins extending through said flanges into said space rearwardly beyond the forward end of said slot for engaging said shoe when said shoe is extended through said slot, means for moving said shoe from a position beyond said drum to a position in which said shoe extends into said slot for engagement by said pins, and a station-

ary cam enclosed within said drum for contacting and disengaging said shoe from said pins during rotation of said drum.

6. In a joint breaker having a rotary drum provided with a slot extending circumferentially, a longitudinally movable jerk line; a shoe attached to said jerk line for operation by said drum to move said jerk line longitudinally in one direction, and a stationary cam supported within said rotary drum; two axially alined removable pins supported by said drum rearwardly beyond the forward end of said slot and having their adjacent ends separated by an intervening space for receiving the body of said shoe when said shoe is extended through said slot, hooks integral with said shoe for engagement by said pins to move said shoe with said drum and thereby move said jerk line longitudinally as aforesaid, and shoulders integral with said drum separated by an intervening space receiving the body of said shoe and engaging the rear and inner circumferential portions of said pins to prevent deformation of said pins by said shoe and by said hooks.

7. In a joint breaker having a rotary drum provided with a circumferential slot, a longitudinally movable jerk line; a shoe attached to said jerk line for operation to move said jerk line longitudinally in one direction during rotation of said drum, and a pair of hooks integral with said shoe; two axially alined removable pins supported by said drum and having their inner ends separated by an intervening space for receiving said shoe and for engaging said hooks to move said shoe with said drum and thereby move said jerk line longitudinally as aforesaid when said shoe extends into said slot, means for moving said shoe to a position in which said shoe extends into said slot, formations on said drum engaging the rear and inner circumferential portions of said pins and preventing deformation of said pins by said hooks, and releasable elements attached to said drum holding said pins from displacement.

8. In a joint breaker having a rotary drum, a longitudinally movable jerk line, and a shoe attached to said jerk line for movement in a planetary orbit about the axis of said drum to move said jerk line longitudinally in one direction; a pair of axially alined pins supported by said drum and separated by an intervening space for receiving said shoe, formations integral with said drum engaging the rear and inner peripheral surface portions of said pins and leaving the forward and outer peripheral portions of said pins exposed for engagement with said shoe, hooks on said shoe for engaging said forward and outer exposed portions of said pins forwardly and outwardly beyond said formations, and a device for supporting said shoe out of position in which said pins will engage said hooks and for moving said shoe to a position in which said pins will engage said hooks during rotation of said drum.

9. In a joint breaker having a rotary drum, a longitudinally movable jerk line, and a shoe attached to said jerk line for movement in a planetary orbit about the axis of said drum to move said jerk line longitudinally in one direction; a pair of axially alined pins supported by said drum and separated by an intervening space for receiving said shoe, formations integral with said drum engaging the rear and inner peripheral surface portions of said pins and leaving the forward and outer peripheral portions of said pins exposed for engagement with said shoe, hooks on

said shoe for engaging said forward and outer exposed portions of said pins forwardly and outwardly beyond said formations, a device for supporting said shoe out of position in which said pins will engage said hooks and for moving said shoe to a position in which said pins will engage said hooks during rotation of said drum, members engaging and holding said pins from longitudinal displacement in either direction, and detachable elements secured to said drum holding said members in rigid connection with said drum.

10. In a joint breaker having a rotary drum provided with an elongated circumferential slot, 15 a stationary support about which said drum is mounted for rotation, a rotary device within said support for rotating said drum, a stationary cam rigid with said support inside said drum, a longitudinally movable jerk line, and a shoe attached to said jerk line for movement in a planetary path above the axis of said drum to move said jerk line longitudinally in one direction; a pair of axially alined pins supported by said drum adjacent to the rear end of said slot, mechanism for moving said shoe into said slot for engagement by the forward and outer circumferential portions of said pins, and formations integral with said drum engaging the inner and rear peripheral portions of said pins inwardly and rearwardly beyond said first named portions of said pins that engage said shoe.

11. In a joint breaker having a rotary drum, a longitudinally movable jerk line, and a shoe attached to said jerk line for operation by said drum to move said jerk line longitudinally in one direction; a removable pin supported by and movable with said drum for engaging said shoe to move said jerk line longitudinally as aforesaid, said pin being symmetrical so that it can be turned end for end to equalize the wear on its surface, and a device attached to said drum engaging and holding said pin from longitudinal displacement in either direction.

12. In a joint breaker having a rotary drum, 45 a longitudinally movable jerk line, and a shoe attached to said jerk line for operation by said drum to move said jerk line longitudinally in one direction; a rotatable pin supported by and having a portion thereof extending permanently beyond the periphery of said drum for engaging said shoe to move said jerk line longitudinally while said drum is rotating, and a device attached to said drum engaging and holding said pin from longitudinal displacement and leaving said pin rotative relative to said drum and said device.

13. In a joint breaker having a rotary drum, a longitudinally movable jerk line, and a shoe attached to said jerk line for operation by said drum to move said jerk line longitudinally in one direction; two removable pins supported by and movable with said drum and separated by an intervening space for receiving said shoe, means for moving said shoe into said space for engagement by said pins to move said jerk line longitudinally while said drum is rotating, and devices attached to said drum engaging and holding said respective pins from longitudinal displacement.

14. In a joint breaker having a rotary drum, a longitudinally movable jerk line, and a shoe attached to said jerk line for operation by said drum to move said jerk line longitudinally in one direction; two axially alined rotatable pins supported by and movable with said drum and sep-

11

arated by an intervening space for receiving said shoe, manipulative means for moving said shoe into said space between said pins, parts on said shoe for engaging said pins when said shoe is in said space and moving said jerk line longitudinally, and elements attached to said drum engaging and holding said respective pins from longitudinal displacement and leaving said pins rotative relative to each other and relative to said drum.

15. In a joint breaker having a rotary drum, a longitudinally movable jerk line, and a shoe attached to said jerk line for operation by said drum to move said jerk line longitudinally in one direction; a pair of axially alined pins supported by and movable with said drum for engaging said shoe to move said jerk line longitudinally as aforesaid, each of said pins having a circumferential groove outside of said drum, and an element attached to said drum and engaging in said groove to hold said pin from longitudinal displacement in either direction.

16. In a joint breaker having a rotary drum, a longitudinally movable jerk line, and a shoe attached to said jerk line for operation by said drum to move said jerk line longitudinally in one direction; a pair of axially alined pins supported by and movable with said drum for engaging said shoe to move said jerk line longitudinally as aforesaid, each of said pins having a circumferential groove outside of said drum, and an element attached to said drum and engaging in said groove to hold said pin from longitudinal displacement in either direction and leaving said pin rotative relative to said drum and said element.

17. In a joint breaker having a rotary drum, a longitudinally movable jerk line, and a shoe attached to said jerk line for operation by said drum to move said jerk line longitudinally in one direction; a hollow pin supported by and movable with said drum for engaging said shoe to move said jerk line longitudinally as aforesaid, a cam integral with the inside of said shoe, and a spring device attached to said drum and extending into said pin engaging said cam and holding said pin from longitudinal displacement.

18. In a joint breaker having a rotary drum, a longitudinally movable jerk line, and a shoe

12

attached to said jerk line for operation by said drum to move said jerk line longitudinally in one direction; two axially alined pins supported by and movable with said drum and separated by an intervening space for receiving said shoe and each of said pins having a circumferential groove at the outer side of said drum, elements attached to said drum engaging in said grooves and holding said pins from longitudinal displacement, and means for moving said shoe into said space for engagement by said pins.

19. In a joint breaker having a rotary drum, a longitudinally movable jerk line, and a shoe attached to said jerk line for operation by said drum to move said jerk line longitudinally in one direction; two axially alined hollow pins supported by and movable with said drum and separated by an intervening space for receiving said shoe, means for moving said shoe into said space for engagement by said pins to move said jerk line longitudinally as aforesaid, spring devices attached to said drum extending into said respective pins, and formations in said respective pins engaged by and cooperating with said spring devices for holding said respective pins from relative and other longitudinal displacement.

20. In a joint breaker having a rotary drum, a longitudinally movable jerk line, and a shoe attached to said jerk line for operation by said drum to move said jerk line longitudinally in one direction, a pair of axially alined pins supported by and movable with said drum for engaging said shoe to move said jerk line longitudinally as aforesaid, and formations on said drum engaging the rear and inner peripheral surface portions of said pins to prevent deformation of the same.

JOHN H. SCHREIBER.
